(57) **CLAIM**

The ornamental design for a gaming machine chair having video display screen, as shown and described.

DESCRIPTION

FIG. 1 is a front perspective view of a gaming machine chair having video display screen mounted to a rear portion of a seat showing our new design;

FIG. 2 is a front view of the gaming machine chair having video display screen shown in FIG. 1;

FIG. 3 is a rear view of the gaming machine chair having video display screen shown in FIG. 1;

FIG. 4 is a left view of the gaming machine chair having video display screen shown in FIG. 1;

FIG. 5 is a right view of the gaming machine chair having video display screen shown in FIG. 1;

FIG. 6 is a top view of the gaming machine chair having video display screen shown in FIG. 1;

FIG. 7 is a bottom view of the gaming machine chair having video display screen shown in FIG. 1;

FIG. 8 is a rear perspective view of a gaming machine chair having video display screen shown in FIG. 1;

FIG. 9 is a front perspective view of a gaming machine chair having video display screen mounted to a rear portion of a seat showing our new design;

FIG. 10 is a front view of the gaming machine chair having video display screen shown in FIG. 9;

FIG. 11 is a rear view of the gaming machine chair having video display screen shown in FIG. 9;

FIG. 12 is a left view of the gaming machine chair having video display screen shown in FIG. 9;

FIG. 13 is a right view of the gaming machine chair having video display screen shown in FIG. 9;

FIG. 14 is a top view of the gaming machine chair having video display screen shown in FIG. 9;

FIG. 15 is a bottom view of the gaming machine chair having video display screen shown in FIG. 9; and,

FIG. 16 is a rear perspective view of a gaming machine chair having video display screen shown in FIG. 9.

The broken lines shown in the figures depicting the gaming machine chair having video display screen support pedestal form no part of the claimed design. The remaining broken lines in the figures depicting lines of stitching on the gaming machine chair having video display screen itself form no part of the claimed design.
